RESILIENT CONNECTOR AND SUPPORT FOR
FRANGIBLE BODIESCortland W. Davis, Alexandria, Ind., assignor to
The Mantle Lamp Company of America, Chi-
cago, Ill., a corporation of Illinois

Application January 27, 1936, Serial No. 61,006

4 Claims. (Cl. 240—83)

My invention pertains to connectors for attaching bodies of frangible material, for example, glass bowls of oil lamps, to bases, and consists of a connector stamped and formed from thin sheet metal, having a first and upwardly extending flange of relatively large diameter, for attachment to the oil-holding vitreous bowl of the lamp, a second and downwardly extending flange of relatively small diameter, for attachment to the upper end portion of the lamp base, and a flat annular diaphragm extending horizontally from the lower end of said first flange to the upper end of said second flange, said diaphragm being of substantial width radially, and, when connected for use with the lamp bowl and base, being free from restraint by any of the parts of the complete lamp, excepting at its outer and inner flanged edge portions. As a result, the annular diaphragm is free to flex or bend under impacts or shocks exerted on either of its flanges by corresponding impacts or shocks on the bowl or base as the case may be, thus avoiding the communicating of resultant impacts or shocks through said diaphragm to the other of said flanges, that might be dangerous to the part of the lamp connected therewith.

The bowls of lamps of the kind referred to, are usually made of glass or vitreous material by blowing, and consequently are not provided with thicker walls than required to give them stability when properly used. They are, therefore, relatively frangible and easily broken by impacts and shocks, which produce greater strains in their structure than result from the proper use of the lamps, whether said impacts and shocks are exerted directly on the bowls, or on bases usually rigidly secured to the bowls. Furthermore, the bases of the lamps even when made of vitreous material, are of more rugged construction than the bowls, and where the bowls and bases are rigidly connected, the bowls are the parts that are damaged by dangerous impacts and shocks, whether they are exerted on the bowls or the bases.

By my invention the bowl of the lamp has a cushioned connection with the lamp base, which is sufficiently flexible and resilient to protect the bowl from damage, thereby avoiding the dangers of such damage or breakage, whether the impacts and shocks protected against are primarily exerted on the bowl or on the base.

My invention will be best understood by reference to the accompanying drawing illustrating a preferred embodiment thereof, in which—

Fig. 1 illustrates in vertical, central, sectional

view an oil lamp in accordance with my invention;

Fig. 2 shows in a view similar to Fig. 1 and to enlarged scale the connector construction I employ between the bowl and the base of the lamp, 8 and

Fig. 3 is a plan view of the connecting device removed from the remaining parts of the lamp structure, this view being to a scale larger than that of Fig. 1 and smaller than that of Fig. 2. 10

Similar numerals refer to similar parts throughout the several views.

As shown in Fig. 1, my lamp construction consists of a bowl 10 of glass or other vitreous material, having an opening in its upper portion provided with a threaded collar 11 to receive a burner in the usual manner. The bowl 10 has an annular extension 10a projecting downwardly from its bottom wall and engaged by my connecting device 12 which also engages the upper end portion 13a of the lamp base 13, which may be of any desired material, for example, glass or other vitreous material.

As more clearly shown in Fig. 2, the connecting device 12 consists of a unitary sheet metal stamping of thin and preferably resilient metal, for example, sheet brass, having an inner and downwardly extending flange 12a, an outer and upwardly extending flange 12b, and a horizontally disposed annular diaphragm 12c connecting the upper end of the flange 12a with the lower end of the flange 12b. Said flanges preferably have screw threads formed in them to engage similar screw threads on the base portion 13a and the bowl portion 10a. The lower end portion of the flange 12a is flared outwardly at 12d below the screw threads in said flange, to seat tightly against a similarly shaped surface 13b on the base 13, when the flange 12a is screwed tightly on the upper threaded portion 13a of the base. The upper edge portion of the flange 12b is flared outwardly below the bowl 10, and has secured to its outer edge, the upper edge of a shell 14 of thin sheet metal, by folding the edge of the shell around the flared edge of the flange 12b as shown 45 at 14a, which shell surrounds the connecting device 12 and is for decorative purposes, having no part in the functioning of said connecting device as a cushioning means connecting the bowl and the base of the lamp. The lower portion of the shell 14 is curved inwardly and downwardly to a position closely adjacent the lower edge of the lower flared portion 12d of the connecting device, and the lower edge of said shell has a short flange 14b extending inwardly therefrom under 50

55

but free from the edge of said portion 12d, the inner edge of said flange 14b being a loose fit on the adjacent portion of the base 13, so that said shell may move freely vertically relatively to 5 the edge of the portion 12d, when the annular diaphragm 12c is flexed in cushioning the bowl 10 from the effects of impacts and shocks exerted either on the bowl or on the base. When the flange 12b is screwed on the threaded bowl extension 10a, the folded portion 14a seats against the under surface of the bowl 10 just outside of its extension 10a, to limit the movement of said flange on said bowl extension when said parts are tightly screwed together. For this condition, and 10 with the flared portion 12d tightly screwed against the seat 13b, the flange 14b has the relation to the lower edge of the portion 12d and to the base 13, above described, and the annular diaphragm 12c is preferably unstressed. Suitable 15 cement 16 is preferably placed on the screw threads as indicated, before screwing the parts together, to compensate for any irregularities in the screw threads on the bowl and base extensions and to permanently hold or lock the parts together.

The lower wall 10b of the bowl extension 10a, preferably has a flat and horizontally disposed lower surface, which lower surface is substantially parallel with the annular diaphragm 12c 20 and preferably sufficiently spaced from said diaphragm, so that said lower surface will not have restraining contact with said diaphragm for any flexing of said diaphragm resulting from impacts and shocks that may usually be exerted either on 25 the bowl or on the base of the lamp. To insure that the wall 10b shall not have dangerous contact with the base at any time, the annular diaphragm 12c is located in a plane which is substantially above the upper end surface of the extension 13a of the base. This leaves an annular space in the upper portion of the flange 12a, in which, if desired, a disk 15 of resilient material, for example, paper stock of loose texture, may be disposed, supported by the extension 13a, the 30 plane of the upper surface of said disk if used, being substantially in the plane of the upper surface of the diaphragm 12c. The disk 15 may thus constitute a resilient buffer for engagement by the wall 10b, when and if the bowl or base is subjected to extreme impacts and shocks, thus preventing even under such extreme conditions, direct and dangerous impacts against the bowl wall 10b, the clearance between the disk and the wall 10b being preferably sufficient so that these parts 35 do not make contact with each other for any usual impacts or shocks that may be exerted either on the bowl or on the base of the lamp. The disk 15 may also serve the further purpose of carrying advertising or other reading matter on 40 its upper surface, which may readily be read through the bowl 10, when said bowl, as is usually the case, is made of transparent glass.

It will be observed, that the diaphragm 12c of my connecting device, may flex or bend freely at 45 any place that may be necessary to cushion or relieve impacts and shocks either on the bowl or on the base of the lamp, such, for example, as lateral or downward impacts on the bowl, setting the lamp down too violently, or tipping the lamp 50 over. Where the bowl and the base are rigidly connected, as has heretofore been the common practice, impacts on the bowl readily produce dangerous strains in the bowl at said connection, because of the necessity of reactive movement of 55 the base to avoid such strains, and because of

the inertia of the base preventing such reactive movement in time to avoid the development of said strains. Again, with such rigid connections, impacts or shocks on the base are immediately communicated to the connected part of the bowl, due to the inertia of the bowl and attached parts, either because in some cases, it is impossible for the bowl and attached parts to acquire the movement of the base immediately, when the base is abruptly moved by the impact or shock, or in other cases, because it is impossible for the bowl and attached parts to stop moving immediately, when the base is in motion and its movement is abruptly stopped by the impact or shock, thus in either event developing dangerous strains in the bowl connection that usually crack or break the bowl.

The disadvantages of such rigid connections are overcome by my invention, by permitting relative movement between the bowl or other supported body and the connected base, and at the same time building up a force in the connection, opposing the movement due to the impact or shock, which prevents the development in the bowl connection of dangerous strains due either to the inertia of the base, or of the bowl and its attached parts.

It will be understood that the size and construction of my connecting device depends upon a number of factors, for example, the weight of the bowl and attached parts, the relation of the diameters of the connector flanges to each other, and the thickness, material and temper of the metal of which the connecting device is made. While it is impossible to lay down any rule for constructing the connecting device that will cover all cases, a single instance of practical construction may serve as a guide. In this instance the lamp was of medium size, the bowl flange had a diameter of about $2\frac{3}{4}$ inches and the base flange 35 of the connecting device had a diameter of about $1\frac{5}{8}$ inches, making the radial width of the diaphragm a little over half an inch. The size of the bowl and base were in proportion, substantially of the size shown in Fig. 1. The connecting device was made of sheet brass of medium temper or hardness, somewhat less than $\frac{1}{2}$ of an inch thick. With this construction, the assembled lamp structure was dropped in upright position, a distance of three feet upon a floor, and the impact of the base striking the floor did not injure the bowl in any way. Repeated tests showed the same results. On the other hand, when similar bowls and bases rigidly connected in a manner heretofore considered good practice, were similarly dropped, the result invariably was the 45 breaking of the bowl.

In addition to its above advantages, my improved connecting device, which, if desired, may be employed to give equally effective cushioned support to other frangible bodies than lamp bowls, is inexpensive to construct.

While I have shown my invention in the particular embodiment above described, I do not limit myself to that exact construction, as I may 55 employ equivalents known to the art at the time of the filing of this application, without departing from the scope of the appended claims.

Having thus described my invention, what I claim is:

1. In a construction of the class described, the combination of a frangible body having a support-engaging portion, a base having its upper end near and spaced from said support-engaging portion, and a single connecting device solely and 75

resiliently supporting said body on said base and comprising a diaphragm in a plane crossing the axes of said body and said base and spaced members extending from the plane of said diaphragm 5 and rigidly connected respectively with said support-engaging portion and said base to support said body on said base, said diaphragm being flat and free to flex between said members and having a substantial extent between said members 10 making said diaphragm a shock-protecting support for said frangible body.

2. In a construction of the class described, the combination of a frangible body having a support-engaging portion, a base having its upper 15 end near and spaced from said support-engaging portion, and a single connecting device solely and resiliently supporting said body on said base and comprising a diaphragm in a plane crossing the axes of said body and said base and spaced members extending from the plane of said diaphragm 20 and rigidly connected respectively with said support-engaging portion and said base to support said body on said base, said diaphragm being flat and free to flex between said members and having a substantial extent between said members 25 making said diaphragm a shock-protecting support for said frangible body, said members having threaded engagement respectively with said support-engaging portion and said base.

3. In a construction of the class described, the combination of a frangible body having a support-engaging portion, a base near and spaced from said support-engaging portion, a device connecting said body to said base comprising a dia- 30

phragm in a plane crossing the axes of said body and said base and spaced members rigidly connecting said diaphragm with said support-engaging portion and said base to resiliently support said body on said base, said diaphragm being flat 5 and free to flex between said members and having an extent between said members making said diaphragm a shock-protecting support for said frangible body, and a shell around said device, one end of said shell being connected with said device and its other end being free to move relatively to said connecting device.

4. In a construction of the class described, the combination of a frangible body having a support-engaging portion, a base near and spaced 15 from said support-engaging portion, a device connecting said body to said base comprising a diaphragm in a plane crossing the axes of said body and said base and spaced members rigidly connecting said diaphragm with said support-engaging portion and said base to resiliently support said body on said base, said diaphragm being flat 20 and free to flex between said members and having an extent between said members making said diaphragm a shock-protecting support for 25 said frangible body, and a shell around said device, one end of said shell being connected with said device and its other end being free to move relatively to said connecting device, said members having threaded engagement respectively 30 with said support-engaging portion and said base.
